UNITED STATES PATENT OFFICE

OLIVER S. BOWMAN, OF COLORADO SPRINGS, COLORADO

RESILIENT HARD-SURFACED FLOOR

Application filed December 13, 1929. Serial No. 413,775.

This invention relates to improvements in floor constructions of the general type shown and claimed in U. S. Letters Patent No. 1,539,988, granted to me on June 2, 1925.

It is the object of this invention to produce a floor construction in which the surface is formed by hard composition blocks preferably of concrete construction and which is supported from a rigid unyielding surface by yielding means which permits the floor surface to bend when a weight is applied thereto and which therefore has the same yielding and resilient properties as are now inherent in wooden floors supported on wooden joists. It has long been recognized that the rigid floors that are quite extensively employed in fireproof building construction, are objectionable for the reason that owing to their unyielding nature, they are very tiresome for the person using them.

Another object of this invention is to produce an improved means for anchoring the composition floors to a flexible wooden base so that it will be securely held to the latter when it flexes due to the weight supported thereby and which also permits a hinge-like action between the separate blocks of the floor structure whereby the floor may yield without cracking or otherwise injuring the hard surface floor that is supported on the flexible base.

Another object of this invention is to produce an improved anchoring means for holding blocks to the flexible base and for holding the separating strips in proper relation until the cement mixture from which the blocks are made is put into place.

The above and other objects that may become apparent as the description proceeds, are attained by means of a construction and an arrangement of parts that will now be described in detail, reference for this purpose being had to the accompanying drawing in which the invention has been illustrated, and in which:

Fig. 1 is a section taken on line 1—1, Fig. 2, and shows one form of my improved floor construction;

Fig. 2 is a top plan view of a portion of the finished floor surface showing the location

of the anchoring means and the separating and anchoring strips;

Fig. 3 is a transverse section of a modification of my invention;

Fig. 4 is a section taken on line 4—4, Fig. 2, and shows one of my improved anchoring devices in place;

Fig. 5 is a section taken on line 5—5, Fig. 4, and shows a cross section of my improved anchoring device;

Fig. 6 is a diametrical section of a slightly modified form of anchoring device;

Fig. 7 is a view similar to that shown in Fig. 4 and shows another form of anchoring device;

Fig. 8 is a view showing the crossing of the two separating strips and showing also the anchoring means illustrated in Fig. 7 as it is just before it is put in place; and

Fig. 9 is a transverse section taken on line 9—9, Fig. 8.

In the drawing reference numeral 1 represents the support which may be a solid concrete slab such as the floor of a fireproof building. The hard surface floor which forms the subject of my invention consists of a layer of composition 2 which, in the present instance, is composed of sand and cement with a top surface of cement and gravel. This is moulded in place in a manner which will

hereinafter be more fully described. The flooring member 2 is supported on the upper surface of a layer of waterproof material 3, which may be tar paper or some similar waterproof fabric. The waterproof material

3 in turn is supported on the upper surface of the flexible wooden base 4 that is formed from sheathing or may be formed from tongue and grooved material or from shiplap, as the exact kind of material is immaterial. Supported on the upper surface of

supporting member 1 are a plurality of strips 5 of wood fiber or any other fibrous yielding material of this nature. If wood fiber is used, it should be of the loose spongy type

such as is used for heat insulation as it is essential that it shall yield when subjected to pressure. Instead of wood fiber it is possible to use material formed from bagasse and

which is now extensively manufactured and

used for heat insulating properties. Strips 6 are secured to the under side of the sheathing 4 for the purpose of holding the flexible base 4 in assembled relation and also for the further purpose of serving as stops to prevent excessive compression of resilient fibrous supports 5.

After the strips 5 have been put in place on the supporting surface 1, and the flexible base 4 assembled and supported thereon, the 10 waterproof material 3 is secured to the upper surface of the base 4. The anchoring devices 7 are now put in place at such positions that they form squares as shown in Fig. 2, or they 15 may form hexagons or triangles, if desired. The anchoring devices are formed from metal and are provided at their lower ends with screw threaded portions 8 that are constructed like an ordinary wood screw. Members 7 20 are provided with a plurality of radial notches 9, the number of which depends on the shape of the block which is to be employed in the floor construction. When a square block is used, the anchoring members have 25 four grooves or slots 9, but where hexagons or triangles are employed the number suitable for the shaped blocks must be provided. For the purpose of this explanation the shape 30 of the blocks 10 will be considered to be square. After the anchoring devices have been put in place and properly leveled, separating strips 12 are put into place between the different anchoring devices. These strips have their ends provided with projecting portions 13 that are adapted to extend into the 35 grooves or notches 9. After the separating strips have been put in place, the cap 14 is then attached to the anchoring devices as shown in Fig. 4. These caps are provided 40 with central plugs 15 that are adapted to fit the openings 16 provided for their reception. The relative diameter of the plugs 15 and the openings 16 is such that the plugs must be forced thereinto and sufficient friction will, 45 thereby be produced to hold them in place. In Fig. 6 I have shown an anchoring device that is constructed like the one shown in Fig. 4 with this exception, that the outer surface is corrugated as indicated by reference numeral 19 and the plugs 15 are threaded as indicated by reference numeral 20. When plugs of this type are used, openings 16 must also be threaded so as to co- 50 operate with the threaded plug. The caps 14 may be square, round or hexagonal, as may be desired. In Figs. 7, 8 and 9 I have shown a modified form of anchoring means. When this anchoring means is employed, the 55 separators instead of having a length equal to the distance between the anchors, may have a length that is the multiple of this distance. The separators shown in Figs. 7 and 8 have been designated by reference 12a and 12b. Each of these is provided with notches 21 on one side and strips 12 have a notch 22 that

extends upwardly from the bottom thereof. Strip 12b has a narrow notch 23 that extends downwardly from the bottom of notch 21. The two strips 12a and 12b can be crossed in the manner shown and notch 22 will receive the lower portion of strip 12b, while notch 23 will receive a portion of strip 12a. At the crossing of the strip, an anchoring device is put in place for the purpose of holding them in adjusted position. This anchoring device has been designated by reference numeral 24 and is preferably formed from a cylindrical body having two diametrical slots 25 that cross each other at right angles. Two of the sector shaped portions between the slots project downwardly beneath the other sector shaped portions and are sharpened at their points as indicated by numeral 26. When these anchoring devices are put in place, the pointed portions 26 are driven into the flexible base 4 and hold the separator strips in aligned position, in the manner shown in Fig. 7. The anchoring devices can be leveled by employing shims in a manner quite apparent, and in this manner the floor surface can be made level. After the anchoring devices and separator strips have been put in place, the spaces between the separator strips is filled with a concrete mixture comprising sand and cement. The upper surface is formed from a layer of cement and gravel that is free from sand, as such a mixture can be polished and is very hard and wear resisting. After the cement has been properly cured, the surface is ground by means of a suitable machine so as to produce a smooth polished surface that resembles terrazzo, but which has been found to be much harder and more durable than terrazzo formed from cement and marble chips and besides this it is much cheaper for the reason that the gravel that is used in the upper or finishing layer is obtained from the sand itself by means of differential screening.

In Fig. 3 I have shown a cross section of a slightly modified construction. In this construction the floor instead of being supported on an unyielding concrete base like that shown in Fig. 1, is supported on wooden joists 27 which are resilient and it is therefore not necessary to employ the fibrous spacers shown in Fig. 1. When the construction illustrated in Fig. 3 is used, the flexible wooden base 4 is supported directly on the joists but in other respects the floor construction is the same as that shown and described.

From the above description it will be apparent that I have produced a floor construction having a hard polished surface, but which will yield when pressure is applied to it and which will therefore be much easier on the people who must stand on it than if an unyielding surface like the surface of the

concrete support 1 served as the floor surface.

The floor surface is moulded in place as above described and the sections 10 are therefore not made separately as in tile floor construction and therefore the term "block" or "blocks" when used in the specification should not be construed as preformed blocks, but as sections of the moulded floor.

10 The strips 12 are a part of the anchoring means and cooperate with members 7 to hold the sections in place.

Having described the invention what is claimed as new is:

15 1. A flexible, resilient floor construction comprising a rigid support, strips of resilient fibrous material resting on the upper surface of the support and spaced apart, a flexible wooden base resting on the upper 20 surface of the fibrous strips, the upper surface of the base being provided with a layer of waterproof material, cement floor sections located on the upper surface of the waterproof material and means for anchoring the 25 edges of the sections to the base, said anchoring means comprising elongated members having their sides provided with radial grooves, the lower ends having threaded projections and the upper ends being provided 30 with openings for the reception of a plug having an enlarged head, said anchoring means being interconnected by metal strips that form compartments for the reception of the concrete mixture.

35 2. A floor construction of the class described comprising, in combination, a flexible supporting base, waterproofing material on the upper surface thereof, a plurality of anchoring devices secured to the upper 40 surface of the base in spaced relation, separating strips extending between the anchoring devices whereby compartments are formed for the reception of a concrete mixture and a resilient yielding support for the 45 flexible base.

50 3. A floor construction of the class described comprising, in combination, a flexible supporting base, waterproofing material on the upper surface thereof, a plurality of anchoring devices secured to the upper 55 surface of the base in spaced relation, said anchoring devices comprising a metal body member provided at one end with a pointed projection adapted to be inserted into the base and at the other end with an opening for the reception of the plug portion of a removable cap, the sides of the anchoring devices having radial grooves, separator strips extending between the different anchoring 60 devices whereby compartments are formed for the reception of concrete and a resilient support for said base.

65 4. A flexible, resilient floor construction comprising a rigid support, strips of resilient fibrous material resting on the upper surface

of the support and spaced apart, a flexible wooden base resting on the upper surface of the fibrous strips, the upper surface of the base being provided with a layer of waterproof material, cement floor sections located on the upper surface of the waterproof material and means for anchoring the edges of the sections to the base, said anchoring means comprising elongated members having two substantially parallel side members spaced apart and pointed at their lower ends, said anchoring means being interconnected by metal strips that form compartments for the reception of the concrete mixture.

70 5. A floor construction of the class described comprising, in combination, a flexible supporting base, waterproofing material on the upper surface thereof, a plurality of anchoring devices secured to the upper 75 surface of the base in spaced relation, said anchoring devices comprising a metal body member provided at one end with pointed projections adapted to be inserted into the base and having radial grooves adapted to receive separating strips, and separating 80 strips extending between the different anchoring devices whereby compartments are formed for the reception of concrete, and a 85 resilient support for the base.

In testimony whereof I affix my signature. 90
